UNITED STATES PATENT OFFICE.

WILLIAM DIETZ, OF CEMENT, TEXAS.

HYDROCARBON-BURNER.

978,860.

Specification of Letters Patent. Patented Dec. 20, 1910.

Application filed June 23, 1910. Serial No. 568,427.

To all whom it may concern:

Be it known that I, WILLIAM DIETZ, citizen of the United States, residing at Cement, in the county of Dallas and State of Texas, have invented certain new and useful Improvements in Hydrocarbon-Burners, of which the following is a specification.

My invention relates to new and useful improvements in hydrocarbon burners and more particularly to hydrocarbon burners used in cement kilns where horizontal rotating cylinders are used.

The object of my invention is to provide a burner of the class described that will be so constructed that the air or steam used in burning the oil can be regulated independently of the oil supply.

Another object of my invention is to provide a burner that will allow a comparatively fine adjustment to be made to regulate the oil supply.

Still another object of my invention is to provide a burner of the character described that will provide means for regulating the area or volume of the flame after it has left the nozzle independent of the air or oil supply.

Finally the object of the invention is to provide means of the character described that will be strong, durable, efficient, and easy of operation, simple and comparatively inexpensive to construct, and also in which the several parts will not be likely to get out of working order.

With the above and other objects in view, the invention has relation to certain novel features of construction and operation, an example of which is described in this specification and illustrated in the accompanying drawings, wherein:

Figure 1. is a longitudinal section of my burner, Fig. 2. is a transverse section on the line S—D of Fig. 1, and Fig. 3. is an end elevation showing the nozzle with the deflector removed.

In the drawings, the numeral 1 designates an air supply pipe communicating at one end with a T joint 2 which in turn is adapted to receive connection from a main air supply. A coupling 3 screw threaded on the other end of the air pipe 1 is fixed on a sleeve 4 and carries a web 5 which forms a hand wheel. The sleeve 4 terminates in a nozzle 6.

Within the air supply pipe 1 and the sleeve 4 an oil supply pipe 7 is supported and terminates in a T joint 8 after passing through a plug 9 which is screw threaded in the T joint 2. The T joint 8 is adapted to be connected with a main source of oil supply and is closed at its rearward end by a packing gland 10. At its forward end the oil supply pipe 7 has connection with a tip 11. This tip is enlarged at 12 to form the bearing on which the nozzle head 6 may be slid by turning the hand wheel 5 and the coupling 3 on the threads of the air supply pipe 1. This adjustment reduces the supply of the air which passes through apertures 14 in the burner tip 11 by bringing the deflecting wall 15 of the nozzle 6 into closer relation with the inwardly extending radial flange 16 carried on the end of the tip 11.

Within the oil supply pipe 7 a sleeve 17 extends. This sleeve is screw threaded into the packing gland 10 and carries at its outer end a hand wheel 18. Where the sleeve 17 extends through the packing gland 10 the oil in the supply pipe 7 is prevented from leaking out by a packing 19 held in position by a follower 20 which is screw threaded into the gland 10. At its forward end the sleeve 17 terminates in an oil regulating sleeve 21 which supports at its forward end an annular flange 22 having an inclined face 23 corresponding to the inclination of the radial flange 16 carried on the end of the tip 11.

The regulator sleeve is provided with a bearing ring 23 near its center which is adapted to slide within the tip 11. Apertures 24 in the ring 23 allow the oil from the pipe 7 to pass from the tip 11 between the flanges 16 and 22 where it may be mixed with the air passing from the supply pipe 1 through the nozzle head 6 between the flange 16 and the deflecting wall 15. The inclination of the deflecting wall 15 and the flanges 16 and 22 cause the air and oil to be thrown to the center and afford a thorough mixing of the air and oil as well as concentration of the fuel toward a common point.

The oil regulating sleeve may be adjusted to increase or diminish the supply of oil by turning the hand wheel 18 and the sleeve 17 thereby causing the threads 25 which engage with threads in the packing gland 10 to move the sleeve forwardly or rearwardly

and to slide the bearing ring 23 in the tip 11. This operation will change the relation of the flange 22 with the flange 16 to give the desired amount of fuel.

5. A rod 26 passes through the sleeve 17 and the sleeve 21 carrying at its forward end a concaved deflector 27. Near its internal end the rod 26 is screw threaded to engage with internal threads in the hand wheel 18 and 10 extends through the same. Where the rod 26 passes through the hand wheel 18 a packing 28 is provided to prevent the leakage of fuel and this packing is held in position by a follower 29. On the rearmost extremity 15 of the rod 26 a hand wheel 30 is mounted. By turning this hand wheel the rod will be moved longitudinally by its screw threaded engagement with the hand wheel 18 to regulate the proper positioning of the deflector 27.

It is obvious that when the deflector 27 is drawn in as is shown in Fig. 1 toward the center of the deflecting wall 15 and the flanges 16 and 22 the combustible mixture 25 will strike the concaved face of the deflector 27 and will be thrown against the angular wall 31 of the nozzle head 6 affording a short flame with a more concentrated heat, while if the deflector is pushed forward a 30 much longer flame may be had. It is also obvious that where steam is used to assist in burning the oil in this burner, that the steam within the supply pipe 1 and sleeve 4 which surrounds the oil supply pipe will superheat 35 the oil vaporizing the same to a certain degree and rendering it more combustible.

What I claim is:

1. In a hydrocarbon burner, an air supply pipe, a nozzle head adjustably connected 40 with the air pipe, a fuel supply pipe extending through the air pipe, a tip carried by the fuel pipe within the nozzle, a perforated bearing ring provided on the tip and on which the nozzle head is adjustable, a fuel 45 regulating sleeve carried within the tip, a connection extending from the regulating sleeve through the fuel pipe to the rear end thereof, a device attached to the connection for adjusting the regulating sleeve, a rod 50 passing through the fuel pipe and the regulating sleeve, a deflector carried on the forward end of the rod, and a device attached to the rod adjacent the first named device for adjusting the rod and the deflector.

55. 2. In a hydrocarbon burner, an air supply pipe, a nozzle adjustably connected with the air pipe, a fuel pipe extending through the air pipe, a tip connected to the fuel supply pipe and located within the nozzle, a perforated bearing ring provided on the tip and on which the nozzle is adjustable, a fuel 60 regulating sleeve movable within the tip, a tubular member connected at its forward end to the regulating sleeve and extending

through the fuel pipe and projecting beyond the rear end thereof, a hand wheel on the rear end of the member, a rod extending through the sleeve and the tubular member and having its ends projecting, a deflector provided on the forward end of the rod adjacent the nozzle, and a hand wheel provided on the rear end of the rod adjacent the first named hand wheel.

3. In a hydrocarbon burner, an air pipe closed at its rear end and having an inlet 75 in its side, a nozzle, an adjustable connection between the air pipe and the nozzle, a fuel supply pipe extending through the closed end of the pipe, a tip within the nozzle connected to the forward end of the 80 fuel pipe, a perforated bearing ring surrounding the tip and fitting the inner walls of the nozzle, a fuel regulating sleeve movable within the tip, a perforated bearing surrounding the sleeve and engaging within 85 the tip, a tubular member connected at its forward end to the sleeve and extending through and beyond the fuel pipe at its rear end, a packing gland at the rear end of the fuel pipe and through which the tubular 90 member extends, a rod extending through the sleeve and the member, a deflector provided on the forward end of the rod, a hand wheel provided on the rear end of the tubular member and through which the 95 rod extends, a packing gland in the hand wheel about the rod, and a second hand wheel secured on the rear end of the rod.

4. In a hydrocarbon burner, a nozzle head having at its mouth a contracted opening 100 and provided with walls converging toward and diverging from the opening, a tip within the nozzle head and having its discharge end contracted and adjacent the converging wall of the nozzle head, an air supply pipe 105 communicating with the space between the nozzle and the tip, means for adjusting the nozzle head with relation to the tip, a regulating sleeve within the tip, an angular portion on the sleeve lying within the contracted end of the tip, a fuel supply pipe connected to the tip, means for adjusting the sleeve with relation to the tip, and a deflector adjacent the diverging wall of the 110 nozzle head.

5. In a hydrocarbon burner, a nozzle head having at its mouth a contracted opening 115 and provided with walls converging toward and diverging from the opening, a tip within the nozzle head and having its discharge 120 end contracted and adjacent the converging wall of the nozzle head, an air supply pipe communicating with the space between the nozzle and the tip, means for adjusting the nozzle head with relation to the tip a regulating sleeve within the tip, an angular portion on the sleeve lying within the contracted end of the tip, a fuel supply pipe con-

ected to the tip, means for adjusting the sleeve with relation to the tip, a deflector having its inner side concaved and being disposed in front of the opening of the 5 nozzle head and adjacent the diverging wall thereof, and means for adjusting the deflector with relation to the diverging wall of the nozzle head.

In testimony whereof I have signed my name to this specification in the presence of 10 two subscribing witnesses.

WILLIAM DIETZ.
